(57) **CLAIM**

We claim, the ornamental design for an image display device, as shown and described.

DESCRIPTION

FIG. 1 is a front view of an image display device showing our new design;

FIG. 2 is a rear view;

FIG. 3 is a right side view;

FIG. 4 is a left side view;

FIG. 5 is a top view;

FIG. 6 is a bottom view;

FIG. 7 is a perspective view in a half-folded state;

FIG. 8 is a perspective view in an unfolded state; and,

FIG. 9 is another perspective view in a curved state.

The image display device is used in a folded, unfolded, or curved state as necessary.

The image display device includes a flexible display that can be curved. The flexible display can function as a touch panel. The flexible display is held by two housings. The image display device can be folded in half with a display surface of the flexible display facing inward.

1 Claim, 5 Drawing Sheets
